Specification for Design.

Patented Mar. 7, 1922.

Application filed July 11, 1921. Serial No. 483,965. Term of patent 3½ years.

To all whom it may concern:

Be it known that I, ALBERT G. SAART, a citizen of the United States, residing at Attleboro, in the county of Bristol and State of Massachusetts, have invented a certain new, original, and ornamental Design for a Topple Die, of which the following is a specification.

In the accompanying drawings which form a part of this specification,

Figure 1 is a side elevation of a topple die embodying my design,

Figure 2 is a similar elevation of the same wherein the die is turned at an angle to the position shown in Figure 1, and

Figures 3 and 4 are, a top plan view and an inverted plan view respectively of the same.

I claim:

The ornamental design for a topple die, as shown.

ALBERT G. SAART.
